ORTHOPTIC APPARATUS

Theodore J. Arneson, Jr., Minneapolis, Minn.

Application April 22, 1946, Serial No. 663,768

17 Claims. (Cl. 128—76.5)

1

My invention relates to orthoptic apparatus and particularly apparatus used for orthoptic diagnosis and treatment.

An object of the invention resides in providing an apparatus having a rotatable plate with a chart thereon and which is adapted to be viewed by the patient through suitable lenses or prisms during diagnosis and treatment.

Another object of the invention resides in providing an apparatus in which the plate may be driven in either a clockwise or counterclockwise direction.

A still further object of the invention resides in providing an apparatus in which the plate may be rotated at various rates of speed.

Another object of the invention resides in providing an apparatus which may be manually adjusted by the patient.

A still further object of the invention resides in providing a motor-driven apparatus which will be extremely quiet in operation.

A feature of the invention resides in constructing the chart on the plate with a target eccentrically disposed relative to the axis of the plate and in providing means for illuminating the target apart from the remainder of the chart.

Other objects of the invention reside in the novel combination and arrangement of parts and in the details of construction hereinafter illustrated and/or described.

In the drawings:

Fig. 1 is an elevational view of an apparatus used for orthoptic diagnosis and treatment and illustrating an embodiment of my invention.

Fig. 2 is a view similar to Fig. 1 of a portion of the structure shown therein, with the plate having the chart thereon removed from the instrument, said view being drawn to a greater scale.

Fig. 3 is a plan sectional view taken on line 3—3 of Fig. 1 and drawn to the same scale as Fig. 2, the section line for this view being also indicated on Fig. 2.

Fig. 4 is a sectional elevational view taken on line 4—4 of Fig. 3 and drawn to the same scale.

The invention consists of a plate 20 having a chart 10 thereon, which plate is rotatably supported and driven by a transmission 11 partly contained in a case 12. The case 12 is mounted on a standard 13 which is carried by a stand 14. The stand 14 consists of three legs 16 which have up-turned portions 17 overlying the standard 13. These portions are welded or otherwise secured to the standard 13.

The case 12 comprises a rear wall 21, a top

wall 22, a bottom wall 23 and side walls 24, the said case being open at the front. By means of this construction a compartment 29 is formed within the case. A plate 25 forms a closure for the open front of the case and is attached to the walls 22, 23 and 24 by means of screws 26 which pass through said plate and are screwed into lugs 27 formed at the corners of the said top wall, bottom wall and side walls. The bottom wall 23 has formed on it a boss 119 in which the standard 13 is received and by means of which the case 12 is supported.

The closure 25 has mounted on it a tubular bearing 31 which is provided with a flange 32 overlying the interior of the said closure and secured thereto by means of screws 33 which extend through said flange and are screwed into said closure. The bearing 31 rotatably supports a shaft 34 which has secured to its outermost end a hub 35. This hub engages the end of the bearing 31 and restrains axial movement of the shaft in one direction. A pin 36 extending through said shaft at the other end restrains axial movement in the opposite direction. A wheel 37 is carried by the hub 35 and is provided with a web 30 and with a flange 40 extending outwardly therefrom. The plate 20 on which the chart is formed is in the shape of a disc which may be constructed of sheet metal or any other suitable material. The plate 20 on which the chart is formed is attached to the web 30 of wheel 37 by cementing the same thereto so that no screws or other fastening means are visible from the face of the chart. Printed or otherwise formed on the outer surface of the plate 20 is a colored zone 127 which extends across the plate substantially from one side to the other. Extending up to the zone 127 are other colored zones 128, 129 and 131 which terminate at the outer periphery of the plate. At the one end of zone 127 is placed a target 132 which has a colored band 133 in the form of an annulus. This annulus may, if desired, be raised from the surface of the disc or the same may lie in the plane thereof. In the center of the target is provided a jewel 134 which is adapted to be illuminated by means of an electric light bulb 151 placed in the back of the same, and shown in Fig. 5 of the drawings. This bulb is mounted in a socket 152 which is attached to the plate 20. The target 132 is mounted on a mounting 153 which is detachably secured to plate 20 by means of a number of fasteners indicated at 153. The various zones on the plate 20 and the target 132 constitute the chart 10.

For operating the apparatus, an electric motor

38 is employed which is disposed within the compartment 29 in case 12 and which is attached to the closure 25 by means of studs 39 which are screwed into said motor. These studs pass through bushings 41 mounted in the closure 25 and are held in place by means of nuts 42 screwed upon the ends of said studs. The motor 38 includes a shaft 43 which extends through an opening 44 in the closure 25 and projects outwardly beyond said closure.

The transmission 11 includes an arm 45 located within the compartment 29 and which is pivoted for swinging movement on a stud 46 secured to the closure 25 of the case. This arm has secured to it a stub shaft 47 on which is rotatably mounted a sheave assembly 48. This sheave assembly includes a sleeve 49 which has attached to the ends thereof beveled flanges 51 and 52, the bevels of which face each other. Mounted between the said flanges and slidably longitudinally along the sleeve 49 is a conical member 53 having beveled surfaces facing the corresponding surfaces of the flanges 51 and 52. These surfaces provide two grooves 54 and 55 between the flange 51 and the member 53 and between said member and the flange 52. The member 53 is frictionally held in place upon the sleeve 49 by means of a spring pressed ball 60. A V-belt 56 is received in the groove 55 and passes over a sheave 57 mounted on the end of the shaft 43 of motor 38.

For rotating the chart 10, a countershaft 58 is employed. This countershaft has secured to it an offset sheave 59 by means of a screw 61 screwed into the end of said shaft and urging the hub 62 of said sheave against a shoulder 63 formed on said shaft. The shaft 58 is journaled in a bearing 64 received in a sleeve 65. The sleeve 65 is, in turn, mounted for swinging movement in a bearing 66 which is formed on the closure 25 and which extends inwardly therefrom. The sleeve 65 has attached to its innermost end a cup-shaped operating member 67. This member has secured to it an arm 68, best shown in Fig. 4 and which projects outwardly from said member in the space between the closure 25 and the sheave 59. When the arm 68 is moved in an up and down direction, as viewed in Fig. 4, the sleeve 65 is moving about the axis of the shaft 68. The member 67 is received within a cavity 69 formed in the interior of the sheave 59. A V-belt 71 passes over the sheave 59 and is received in the groove 54 in the sheave assembly 48. It will readily be comprehended that when the arm 45 is swung about the stud 46 as a pivot, that the sheave assembly 48 may be moved toward or from either of the shafts 43 or 58. This causes the conical member 53 to move toward or from either of the flanges 51 or 52 and to vary the width of the grooves 54 and 55. This changes the speed of the countershaft 58. Thus the countershaft 58 may be driven at any desired speed within the range of the device by properly proportioning the arm 45.

The sleeve 65 has secured to the outer end of the same a plate 72 which projects outwardly therefrom. Mounted on this plate are two studs 73 and 74 which rotatably support two sheaves 75 and 76. Mounted on the end of the countershaft 58 is a sheave 77 which has two grooves 78 and 79 therein. The sheave 77 abuts against a shoulder 112 formed on the said shaft and is held attached to said shaft by means of a screw 113 similar to the screw 61. The two sheaves 75 and 76 are arranged in staggered relation. The

sheave 75 is aligned with the groove 78 and the sheave 76 is aligned with groove 79. Received in the grooves 78 and 79 are belts 81 and 82 which pass over the sheaves 75 and 76, respectively.

- 5 The sheaves 75 and 76 have attached to them friction gears or rollers 83 and 84 which straddle the flange 40 of the wheel 37 which serves as a friction gear for coaction with the gears 83 and 84. When the sleeve 65 is swung in one direction about its axis through movement of the lever 68, the gear 83 engages the flange 40 on one side and drives the wheel 37 and shaft 34 in one direction. When the sleeve 65 is shifted in the opposite direction, the gear 83 is disengaged from the flange 40 and the gear 84 engages said flange upon the opposite surface thereof, driving the said wheel in the opposite direction. When both gears are clear of the flange, wheel 37 stops.

Depending from the bottom wall 23 of case 12 is a tubular neck 18. This neck is attached to a control box 15 accessible below the chart 10. A passageway 28 in the neck 18 brings the compartment 28 in case 12 into communication with the interior of the control box 15.

- 25 The control box 15 is shown in detail in Fig. 4 and comprises a top wall 85, a bottom wall 86 and side walls 87, connected together by means of a back wall not shown. The said walls are open at the front and are adapted to be closed by means of a cover 88 held attached to said box by means of screws 89 passing through said cover and threaded into bosses 91 formed in said box. The neck 18 previously referred to issues from the wall 85 of said box. Journaled in bearings 35 not shown but formed in the cover 88 are two shafts 92 and 93. These shafts have attached to their outer end knobs 95 and 94 respectively. The knob 94 has a pointer 96 which is adapted to register with marks 97 on the cover 88. Knob 95 is similarly provided with a pointer 98 which is adapted to register with marks 99 also disposed on the cover 88. The inner end of the shaft 92 has secured to it an eccentric 101 which engages a 45 rod 105 mounted on a swinging arm 103. Arm 103 is pivoted on a stud 104 secured to the cover 88. When the knob 95 is rotated, arm 103 is moved in an up and down direction.

A rod 105 extends along the passageway 28 in neck 18 and into the interior of box 15 and the compartment 29 of case 12. The lower end of this rod passes through the outermost end of the arm 103. Two collars 106 and 107 are secured to this rod on opposite sides of the arm 103 and fit loosely against said arm, so that the rod 105 may be moved in an up and down direction as the shaft 92 is rotated. The upper end of the rod 105 is connected to a bracket 109 secured to arm 45 by means of screws 111. It will thus become readily apparent that as the shaft 92 is turned, rod 105 is reciprocated vertically and the arm 45 swung in a manner to vary the widths of the grooves 54 and 55 and to correspondingly vary the speed of the countershaft 58.

- 65 The shaft 93 has attached to the innermost end of it a disc 114. This disc has pivoted to it a pintle 115 formed on an arm 116. The arm 116 extends outwardly from a rod 117 which, similarly to the rod 105, extends through the passageway 28 in neck 18 and into the compartment 29 within the case 12. The arm 68 in case 12 has attached to it by means of a screw 118 a boss 119 and through which the rod 117 loosely passes. Spacer collars 121 and 122 are secured to said rod on opposite sides of the boss 119.

A compression coil spring 123 is seated at one end against the collar 121, at the other end against the boss 110. A similar spring 124 is seated at one end against the collar 122 and at its other end against the boss 119. The disc 114 serves as a crank, which operating on the pintle 115 reciprocates the rod 117. The said rod through the springs 123 and 124, acts on the boss 119 and raises and lowers the lever 68. This swings the plate 72 which brings one or the other of the rollers 83 or 84 into engagement with the flange 40. Movement of the shaft 93 is limited by means of a pin 108 secured to cover 88. This pin is adapted to engage either of two shoulders 110 formed on the disc 88.

For illuminating the jewel 134 on chart 10, a brush 135 is provided which is mounted in a brush holder 136 secured to the cover plate 25 of case 12. This brush is adapted to engage a slip ring 137 mounted on the hub 35 of wheel 37. The brush 135 is connected to a source of low voltage for energizing the lamp and the slip-ring 137 is electrically connected by means of a conductor 154 to the socket 152, the return for which is grounded through the plate 20, shaft 34 and the bearings of the transmission. The conductor 154 is disposed between the wheel 37 and plate 20 and lies in a groove 155 formed in said wheel.

For illuminating the entire chart 10, an electric bulb 138 is employed which is supported by bracket 139 extending upwardly from the upper wall 22 of the case 12. A reflector 141 is supported on said bracket and directs the light downwardly upon the chart 10. The bracket 139 is constructed hollow and communicates with the compartment 29 within the case 12 where connections for current for operating the said lamp may be provided.

The method of operation is readily apparent. The patient is seated at a locality immediately in front of the apparatus with his eyes at about the elevation of the chart. The practitioner then applies the proper lenses or prisms to the patient and starts the apparatus in operation. The patient in observing the moving chart exercises the muscles of the eyes to correct the fault or weakness of the eyes. After the chart has been rotated for a time in one direction, the patient turns the knob 94 in the opposite direction and reverses the direction of rotation of the chart. As the treatment progresses, the speed of rotation of the chart may be readily varied by the patient or practitioner by merely turning the knob 95 one way or the other.

The advantages of my invention are manifest. The device is extremely simple in construction and positive and effective in operation. By the use of the particular variable speed drive employed, changes in speed of the chart may be procured with ease. The reversing mechanism operates in an extremely simple and effective manner and permits of the patient rapidly changing the direction of rotation of the chart without injuring the apparatus. Due to the arrangement of parts, the transmission between the operating motor and the chart is exceedingly quiet and reduction of speed is procured with a minimum number of parts. Most of the apparatus may be contained within a suitable case, where the same is concealed and protected. The operating members of the invention are located at a convenient elevation for manipulation by the patient and procure through concealed mechanism variation in direction of rotation and speed of the chart.

Changes in the specific form of my invention, as herein described, may be made within the scope of what is claimed without departing from the spirit of my invention.

Having described my invention, what I claim as new and desire to protect by Letters Patent is:

1. In an orthoptic apparatus, a plate having a chart thereon, pivot means for supporting said plate for rotation, a flange issuing outwardly from said plate and concentric with the axis of said pivot means, a swinging support, spaced rollers rotatably mounted on said support and straddling said flange, means for driving said rollers in the same direction of rotation and means for selectively bringing either of said rollers in engagement with said flange.
2. In an orthoptic apparatus, a plate having a chart thereon, pivot means for supporting said plate for rotation, an annular driven member having inner and outer surfaces concentric with the axis of said pivot means, a movable support, spaced rollers rotatably mounted in said support and disposed with one roller adjacent one of said surfaces and the other roller adjacent the other of said surfaces, means for driving said rollers so as to cause the contacting surfaces thereof to travel in opposite directions and means for selectively bringing either of said rollers in engagement with the corresponding surface of said driven member.
3. In an orthoptic apparatus, a plate having a chart thereon, pivot means for supporting said plate for rotation, an annular driven member having inner and outer surfaces concentric with the axis of said pivot means, a swinging support, pivot means therefor, spaced rollers rotatably mounted on said support and straddling said driven member, a rotatable transmission element rotatable about the axis of the pivot means for said support, means for driving said transmission element, driving means between said transmission element and said rollers and causing rotational movement of said rollers in the same direction, and means for swinging said support about its pivot means to bring either of said rollers into engagement with said driven member.
4. In an orthoptic apparatus, a plate having a chart thereon, pivot means for supporting said plate for rotation, an annular driven member having inner and outer surfaces concentric with the axis of said pivot means, a swinging support, pivot means therefor, spaced rollers rotatably mounted on said support and straddling said driven member, a rotatable transmission element rotatable about the axis of the pivot means for said support, means for driving said transmission element, driving means between said transmission element and said rollers and causing rotational movement of said rollers in the same direction, means for swinging said support about its pivot means to bring either of said rollers into engagement with said driven member, and resilient means for holding either of said rollers in engagement with the corresponding surface of said driven member.
5. In an orthoptic apparatus, a plate having a chart thereon, pivot means for supporting said plate for rotation, an annular driven member having inner and outer surfaces concentric with the axis of said pivot means, a swinging support, pivot means therefor, spaced rollers rotatably mounted on said support and straddling said driven member, a rotatable transmission element rotatable about the axis of the pivot means for said support, means for driving said transmission element, driving means between said transmission element and said rollers and causing rotational movement of said rollers in the same direction, means for swinging said support about its pivot means to bring either of said rollers into engagement with said driven member, and resilient means for holding either of said rollers in engagement with the corresponding surface of said driven member.

element, said transmission element including two sheaves, sheaves rotatable with said rollers, belts passing over said first named sheaves and driving said second named sheaves and procuring rotation of said rollers in the same direction and means for swinging said support about its pivot means to bring either of said rollers into engagement with said driven member.

6. In an orthoptic apparatus, a plate having a chart thereon, pivot means for supporting said plate for rotation, an annular driven member having inner and outer surfaces concentric with the axis of said pivot means, a swinging support, pivot means therefor, spaced rollers rotatably mounted on said support and straddling said driven member, a rotatable transmission element rotatable about the axis of the pivot means for the support, driving means between said transmission element and rollers, a sheave on said transmission element, an electric motor, a sheave driven by said motor, a second support, means for guiding said second support for movement in a direction toward and from said sheaves, a sheave assembly rotatably mounted on said second support and comprising two end flanges and a conical member disposed between said flanges and movable axially toward and from the same, said conical member forming with said flanges two sheaves varying in diameter upon the movement of the conical member from one flange to the other, a belt between said transmission element sheave and one of the sheaves of said sheave assembly, a belt between said motor sheave and the other of the sheaves of said sheave assembly and means for shifting said second support to different positions to vary the speed of said transmission element.

7. In an orthoptic apparatus, a case having a wall, a plate having a chart thereon and disposed exteriorly of the case, pivot means for said plate carried by said wall, a bearing carried by said wall, a sleeve pivoted in said bearing and extending through said wall, a shaft extending through said sleeve and journaled for rotation therein, motive means within said case, driving means between said motive means and the inner end of said shaft, an operating member connected to the inner end of said sleeve and serving to rock said sleeve, a reversing drive between the outer end of the shaft and said plate for driving said plate in either direction and means connected to the outer end of said sleeve for operating said reversing drive.

8. In an orthoptic apparatus, a case having a wall, a plate having a chart thereon and disposed exteriorly of the case, pivot means for said plate carried by said wall, a bearing carried by wall, a sleeve pivoted in said bearing and extending through said wall, a shaft extending through said sleeve and journaled for rotation therein, motive means within said case, driving means between said motive means and the inner end of said shaft, a driven member rotatable with said plate, two driving members supported by said sleeve and disposed outwardly of said wall, means for driving said driving members from the outer end of said shaft, said driving members being movable upon rotary movement of said sleeve to selectively engage and drive said driven member in opposite directions and an operating member connected to the inner end of the sleeve and serving to bring either of said driving members into driving relation with said driven member.

9. In an orthoptic apparatus, a case having a wall, a plate having a chart thereon and disposed

exteriorly of the case, pivot means for said plate carried by said wall, a bearing carried by said wall, a sleeve pivoted in said bearing and extending through said wall, a shaft extending through said sleeve and journaled for rotation therein, motive means within said case, driving means between said motive means and the inner end of said shaft, a flange extending outwardly from said plate and rotatable therewith, a support carried by the outer end of said sleeve, two rollers supported for rotation by said support and straddling said flange, means for driving said rollers from the outer end of said shaft and means connected to the inner end of said sleeve for swinging said sleeve and support to bring either of said rollers into engagement with said flange.

10. In an orthoptic apparatus, a case having a wall, a plate having a chart thereon and disposed exteriorly of the case, pivot means for said plate carried by said wall, a bearing carried by wall, a sleeve pivoted in said bearing and extending through said sleeve and journaled for rotation therein, motive means within said case, driving means between said motive means and the inner end of said shaft, a flange extending outwardly from said plate and rotatable therewith, a support carried by the outer end of said sleeve, two rollers supported for rotation by said support and straddling said flange, sheaves rotatable with said rollers, sheaves on the outer end of said shaft and driven thereby, belts passing about corresponding sheaves to simultaneously drive both of said rollers and means connected to the inner end of said sleeve for swinging said sleeve and support to bring either of said rollers into engagement with said flange.

11. In an orthoptic apparatus, a case, a plate having a chart thereon carried by said case and mounted for rotation, motive means for rotating said plate and disposed within the case, a variable speed transmission between said motive means and plate, a tubular neck depending from said case, a control box attached to said neck, operating means carried by said control box and means extending within said neck and connected to said operating means and transmission for regulating the speed of said plate.

12. In an orthoptic apparatus, a case, a plate having a chart thereon carried by said case and mounted for rotation, motive means for rotating said plate and disposed within the case, a reversible transmission between said motive means and plate, a tubular neck depending from said case, a control box attached to said neck, operating means carried by said control box and means extending within said neck and connected to said control means and transmission for changing the direction of rotation of said plate.

13. In an orthoptic apparatus, a case having a wall, a plate disposed exteriorly of the case, pivot means for said plate carried by said wall, a bearing carried by said wall, a sleeve pivoted in said bearing and extending through said wall, an arm attached to said sleeve, a shaft extending through said sleeve and journaled for rotation therein, motive means within said case, driving means between said motive means and the inner end of said shaft, a reversing drive between the outer end of said shaft, a reversing drive between the outer end of said shaft and said plate for driving said plate in either direction, and adapted to be actuated upon swinging of said sleeve, a tubular neck depending from said case, an operating member disposed at the lower end

of said neck and a link disposed within said neck and connected to said operating member and arm and serving to rotate said sleeve and actuate said reversing drive for driving said plate in either direction.

14. In an orthoptic apparatus, a case having a wall, a plate disposed exteriorly of the case, pivot means for said plate carried by said wall, a bearing carried by said wall, a sleeve pivoted in said bearing and extending through said wall, a shaft extending through said sleeve and journaled for rotation therein, motive means within said case, a variable speed drive between said motive means and the inner end of said shaft, a drive between the outer end of said shaft and said plate and including a reversing mechanism, said reversing mechanism being operated upon swinging of said sleeve, a tubular neck depending from said case, two operating members disposed at the lower end of said neck, a link disposed within said neck and connected to one of said operating members and said variable speed drive and a second link disposed within said neck and connected to said second operating member and to said sleeve.

15. In an orthoptic apparatus, a plate having a chart thereon, pivot means for supporting said plate for rotation, said chart comprising a configuration in the form of an E, a target mounted on said plate and located in proximity to the base of said configuration, said target including a jewel located at the center of the same and illuminating means located in back of said jewel and traveling with said plate.

16. In an orthoptic apparatus, a plate having a chart thereon, pivot means for supporting said plate for rotation, said chart comprising a configuration in the form of an E, a target mounted on said plate and located in proximity to the base of said configuration, said target including a jewel located at the center of the same and an annular ring encircling said jewel and illuminating means located in back of said jewel and traveling with said plate.

17. In an orthoptic apparatus, a plate having a chart thereon, pivot means for supporting said plate for rotation, said chart comprising a configuration having a main bar and three other bars spaced from one another and extending angularly from said main bar and in the same direction, a circular target mounted on said plate and located on said main bar at one end thereof, said target including a jewel located at the center of the same and illuminating means located in back of said jewel and traveling with said plate.
